HUGH LAING AND EDWARD WILKINSON ASHBY, OF SUNDERLAND, ENGLAND.

SHIP FOR CARRYING LIQUID CARGOES IN BULK.

1,234,675.

Specification of Letters Patent.

Patented July 24, 1917.

Application filed October 31, 1916. Serial No. 128,690.

To all whom it may concern:

Be it known that we, HUGH LAING and EDWARD WILKINSON ASHBY, subjects of the King of Great Britain and Ireland, residing 5 in Sunderland, in the county of Durham, England, have invented certain new and useful Improvements in Ships for Carrying Liquid Cargoes in Bulk, of which the following is a specification.

10 This invention relates to the special type of ships known as "tankers" which are used for carrying liquid cargoes in bulk, such, for example, as oil or molasses. In "tankers" longitudinal strength is of first 15 importance and the comparatively numerous compartments and close-spaced transverse bulkheads, also the framing and other structural parts, are designed specially and of approved strength to carry liquid cargoes 20 in bulk.

The object of the present invention is to provide an improved bulkhead construction for "tankers" whereby increased longitudinal strength and other advantages are obtained.

In a liquid cargo carrying vessel of the type known as a "tanker" in accordance with this invention, we arrange one or more of the transverse bulkheads so that, where 30 a single longitudinal straight-line bulkhead is provided and the cargo space thus divided into two longitudinal compartments, the portions of the transverse bulkheads crossing the compartments on each side of 35 said longitudinal bulkhead are not in line the one with the other, but are stepped a convenient distance away; and, where two longitudinal straight-line bulkheads are provided and the cargo space divided into 40 three longitudinal compartments, one or more of the bulkheads crossing the center longitudinal compartment are not in line with the bulkheads crossing the side longitudinal compartments, but are stepped a 45 convenient distance away.

We will fully describe our invention with reference to the accompanying drawings wherein—

Figures 1 and 2 are a profile and a plan 50 of a "tanker" or vessel designed to carry liquid cargoes in bulk, provided with two longitudinal straight-line bulkheads and with transverse bulkheads arranged in accordance with our invention; and

55 Figs. 3 and 4 are transverse sections on

the lines *a—a* and *b—b* respectively in Figs. 1 and 2.

Fig. 5 is a transverse section and Figs. 6 and 7 are part plans of "tankers" or oil-carrying vessels with single central longitudinal straight-line bulkheads and transverse bulkheads arranged in accordance 60 with our invention.

In all the figures like letters of reference indicate like parts.

Figs. 1, 2, 3 and 4 illustrate the application 65 of our invention to a vessel having a single deck and two longitudinal bulkheads A, A extending from the after cofferdam W to the forward cofferdam X and from the bottom to the upper deck of the ship but not above same. Abaft the after cofferdam is the machinery space Z, the machinery being placed above the tank Y. In this example the cargo space is divided into three 70 longitudinal compartments F which are subdivided by transverse bulkheads G, H. The bulkheads G which cross the center longitudinal compartment are not in line with the bulkheads H which cross the side longitudinal compartments but are stepped a convenient distance away. If desired the side 75 transverse bulkheads H may also be arranged out of line with each other as well as out of line with the center transverse 80 bulkheads G, as will be readily understood without illustration.

Figs. 5, 6 and 7 illustrate the application 85 of our invention to a vessel having 'tween decks M and a single central longitudinal bulkhead A so that the cargo space is divided into two longitudinal compartments F which are subdivided by transverse bulkheads H. In this case the portions of transverse bulkheads H on each side of the longitudinal bulkhead A are not in line with each other but are stepped a convenient distance 95 away.

With the arrangement of the transverse bulkheads G and H illustrated in Figs. 1 100 to 7, the longitudinal strength of the vessel at a cross section through any transverse bulkhead G or H crossing a cargo space F is increased because the close-spaced rivet holes in the boundary angles L of the transverse bulkheads do not extend in line completely around the whole of the side and bottom plating or across the whole width of the deck as has hitherto been customary in 105 "tankers," but are stepped on either side of 110

the longitudinal bulkhead or bulkheads A, and thus an increased sectional area of material to resist the longitudinal stresses is provided without employing any additional material.

The drawings show vessels constructed with close-spaced side shell longitudinal frames Q, and longitudinal deck beams PC, PS, and bottom frames TC, TS and 10 with longitudinal bulkhead stiffeners E, supported by strong comparatively widely-spaced transverse frames or ribs R between the transverse bulkheads, but the ship may be constructed with the usual 15 transverse framing, or with part transverse and part longitudinal framing. Where we fit two longitudinal bulkheads the stiffeners E are preferably continuous in way of the transverse bulkheads passing uncut across 20 the ends of the transverse bulkheads H, but on the other side thereto of the longitudinal bulkheads A and thus add considerably to the longitudinal strength. In Fig. 3 the deck and bottom longitudinals PC and TC are continuous in way of the transverse 25 bulkheads H and also the longitudinal bulkhead stiffeners E, while the remaining longitudinals on the shell and deck are cut at these bulkheads. In Figs. 4 and 5 the deck 30 and bottom longitudinals PS and TS toward the sides and the side shell longitudinals Q are continuous in way of the part transverse bulkheads. Thus, a good proportion of the 35 longitudinal stiffeners pass the part transverse bulkheads uncut and add considerably to the longitudinal strength and efficiency of the ship's structure, while a saving of weight is effected by the part bulkheads taking the place of some or all of the longitudinal bulkhead vertical webs.

Transverse wash-plates KC, KS (Figs. 3 and 4) or transverse beams RC, RS (Fig. 5) may be fitted below the longitudinal deck-beams PC, PS and in line with the transverse bulkheads G, H. The wash-plates 45 may be attached to the longitudinal deck beams by knee plates and/or suitable lugs thus dispensing with the comparatively wide-spaced rivet holes through the deck which would be necessary if the said portions were connected directly by flanging or by lugs or with intercostal plates to the deck. The transverse floors RC, RS (Figs. 3, 4 and 5) may also be arranged above the bottom frames TC, TS and attached thereto by 50 knee plates and/or lugs.

Where the cargo space is divided into three longitudinal compartments F by two longitudinal watertight bulkheads A, A as 60 illustrated in Figs. 1 to 4 each compartment being about one-third of the vessel's beam, the transverse watertight bulkheads G, H subdividing the three longitudinal compartments are spaced at greater intervals than 65 usually approved of by the Classification So-

cieties for liquid cargo-carrying vessels ("tankers") having only a single longitudinal bulkhead.

The three series of tanks formed by the two longitudinal bulkheads A, A (Figs. 1 to 4) being each about one-third of the beam of the vessel in width, form their own expansion trunks and permit of the omission of the usual expansion trunk extending fore and aft amidships above or below the deck, 70 or of any other trunks adapted to limit the extent of the free surface of the liquid cargo or to allow for expansion of the liquid, sufficient spare capacity for the usual expansion of the liquid when the vessel has a full cargo 75 on board being allowed for by our construction.

Where the cargo space is divided into three longitudinal compartments of about equal capacity as illustrated in Figs. 1 to 4, 85 the effect of the free surface of the liquid cargo on the transverse stability of the ship in the worst condition of loading (that is, when free liquid is present in all the tanks at the same time), is much less than that of 90 the case of an ordinary oil tank vessel fitted with one longitudinal bulkhead at the center line with the surface of the liquid some distance below the bottom of the expansion trunk. All the tanks can be filled with 95 liquid until nearly full, and yet allow sufficient room for expansion, and even then the effect of the free surface of the liquid cargo on the transverse stability would not be such as to endanger the vessel.

When a ship having two longitudinal bulkheads is loaded with liquid cargo of great density and requiring less stowage space, one or more of the central tanks may be entirely emptied while the remaining tanks 105 may be practically full, and the cargo will thus be more equally distributed than is possible in a ship having a single longitudinal bulkhead, and undue straining of the ship is obviated.

In some cases where we fit the ship with two longitudinal watertight bulkheads A, A, we may slope the side portions of the upper deck up to the central level portion in a curved or straight line (as in Figs. 3 and 4), 115 or the sides of the vessel may be inclined inward from about the load waterline up to the upper deck, to a greater extent than usual, to limit the widths of the side compartments at the top.

What we claim and desire to secure by Letters Patent is:—

1. A bulkhead construction for a liquid cargo carrying ship of the type known as a "tanker" comprising not less than one 125 longitudinal bulkhead dividing the cargo space into longitudinal compartments, and not less than one transverse bulkhead subdividing said longitudinal compartments, the portions of each transverse bulkhead 130

- on each side of a longitudinal bulkhead being out of line the one with the other.
2. A bulkhead construction for a liquid cargo carrying ship of the type known as a "tanker" comprising two longitudinal bulkheads formed in straight lines in the fore and aft direction extending from the bottom of the vessel only to the upper deck and dividing the cargo space into three longitudinal compartments, and not less than one transverse bulkhead subdividing said longitudinal compartments, portions of each transverse bulkhead being out of line the one with the other. 5 55
- 10 3. A bulkhead construction for a liquid cargo carrying ship of the type known as a "tanker" comprising two longitudinal bulkheads formed in straight lines in the fore and aft direction dividing the cargo space into three longitudinal compartments, and not less than one transverse bulkhead subdividing said longitudinal compartments, portions of each transverse bulkhead being out of line the one with the other, and 15 60
- 20 25 close-spaced longitudinal stiffeners. 65
4. A bulkhead construction for a liquid cargo carrying ship of the type known as a "tanker" comprising two longitudinal bulkheads formed in straight lines in the fore and aft direction dividing the cargo space into three longitudinal compartments, and not less than one transverse bulkhead subdividing said longitudinal compartments, portions of each transverse bulkhead being out of line the one with the other, and 30 65
- 35 close-spaced longitudinal stiffeners, said longitudinal stiffeners being continuous and arranged on the inner sides of the longitudinal bulkheads. 70
- 40 5. A liquid cargo carrying ship of the type known as a "tanker" having longitudinal deck beams and a bulkhead construction comprising not less than one longitudinal bulkhead dividing the cargo space into longitudinal compartments, and not less than one transverse bulkhead subdividing said longitudinal compartments, the portions of each transverse bulkhead on each side of a longitudinal bulkhead being out of 45 75
- 50 line the one with the other, in combination with transverse wash-plates fitted below said longitudinal deck beams in line with said portions of the transverse bulkheads, said transverse wash-plates being attached to the longitudinal deck beams. 80
6. A liquid cargo carrying ship of the type known as a "tanker" having longitudinal deck beams and a bulkhead construction comprising two longitudinal bulkheads formed in straight lines in the fore and aft direction extending from the bottom of the vessel only to the upper deck and dividing the cargo space into three longitudinal compartments, and not less than one transverse bulkhead subdividing said longitudinal compartments, portions of each transverse bulkhead being out of line the one with the other, in combination with transverse wash-plates fitted below said longitudinal deck beams in line with said portions of the transverse bulkheads, said transverse wash-plates being attached to the longitudinal deck beams. 85
7. A liquid cargo carrying ship of the type known as a "tanker" having longitudinal deck beams and a bulkhead construction comprising two longitudinal bulkheads formed in straight lines in the fore and aft direction dividing the cargo space into three longitudinal compartments, and not less than one transverse bulkhead subdividing said longitudinal compartments, portions of each transverse bulkhead being out of line the one with the other, and close-spaced longitudinal stiffeners, said longitudinal stiffeners being continuous and arranged on the inner sides of the longitudinal bulkheads, in combination with wash-plates fitted below said longitudinal deck beams in line with said portions of the transverse bulkheads, said transverse wash-plates being attached to the longitudinal deck beams. 90

In witness whereof, we have hereunto signed our names in the presence of two subscribing witnesses.
